UNITED STATES PATENT OFFICE.

RAYMOND A. HEISING, OF EAST ORANGE, NEW JERSEY, ASSIGNOR TO WESTERN ELECTRIC COMPANY, INCORPORATED, OF NEW YORK, N. Y., A CORPORATION OF NEW YORK.

MODULATING.

Original application filed September 21, 1915, Serial No. 51,761. Patent No. 1,343,562, dated June 15, 1920. Divided and this application filed June 4, 1920. Serial No. 386,452.

This invention relates to systems for and methods of producing waves whose amplitude varies in accordance with other waves of lower frequency. Such systems are used in telephony and other wave transmission and are commonly known as modulating systems because the waves produced are modulated or varied in accordance with a signaling wave.

- 10 In a preferred form, the invention comprises an oscillation generator of the thermionic type, having a space current or discharge path between a heated filamentary or other cathode, and an anode, together with 15 a discharge controlling element or electrode for controlling the discharge between the cathode and the anode. The usual form of control element is a grid-like structure between the cathode and the anode but the 20 form and position of this element may vary. U. S. Patent to Colpitts, 1,137,384, granted April 27, 1915, is an illustration of this type of modulator. In this patent an arrangement is shown whereby high frequency oscillations are caused to vary in amplitude in accordance with the speech frequency variations of potential impressed upon the grid. The present invention comprises certain improvements in devices of this type.
- 30 In the arrangement herein disclosed modulation of the high frequency oscillations is produced by causing variations in the unidirectional voltage impressed between the anode and the cathode of the oscillator. 35 The circuit is so arranged that similar low frequency variations are caused to occur in both the input and output circuits of the oscillating tube. This is accomplished by providing a microphone, which is a typical 40 form of variable impedance device, in a path common to the input and output circuits. The variable impedance of the microphone when it is acted upon by sound waves acts to vary the effective voltage impressed 45 upon the tube by the space current source, since it is located in a series path containing the space current source and the anode-cathode path of the tube.
- 50 The microphone also acts as an impedance to the high frequency waves generated by the system, which impedance varies in accordance with the sound waves acting there-

on. In any oscillatory system a variation of resistance or amplitude of an element thereof will cause a corresponding variation in amplitude of the oscillations, hence, the microphone will cause modulation by virtue of its variable impedance to the high frequency waves set up.

Application of the principles of the invention is not limited to the specific circuit arrangement herein shown and described, but may be employed in various circuit arrangements within the scope of the appended claims.

For a detailed description of the circuit used, reference is made to the appended drawing, wherein is shown a tuned circuit, comprising inductance 13 and variable capacity 14 connected to a discharge device 70 comprising an evacuated vessel 15, containing a heated filamentary cathode 16, a discharge controlling element 17, and an anode 18. The discharge tube is supplied with space current by the source 20, which is connected in a path external to the tube between the cathode and the anode. The input circuit of the tube comprises a path external to the tube between the cathode and the control electrode, while the output circuit comprises a path between the cathode and the anode. The frequency of the oscillations set up will be principally determined by the magnitude of the self inductance 13 and the capacity 14, while the resistance 35, included in the tuned circuit, may be so adjusted as to bring the oscillations to a small amplitude. The advantage of this is that when the amplitude of the oscillations is small, the relative proportions of the harmonic components, as compared with the fundamental frequency, will be small, and hence the wave produced will approximate a sine-wave. The connection between the cathode and the tuned circuit is to an intermediate point in the inductance 13, as is common in circuits of this type. In this connection are included a resistance 30 in series with a battery 31, around both of which is connected a microphone 32. The battery 31 supplies energizing current to the microphone 32 through the resistance 30. The battery 31, as shown, is connected with respect to the space current path of

the tube in the same direction as the battery 20. The electromotive force of the battery 31, the ohmic value of the resistance 30, and the impedance of the microphone may vary 5 through a wide range of values, but will in general, be chosen so as to give the best results with the particular discharge tube 15 in use, the characteristics of different types of tubes being widely different.

10 It will be seen that the microphone is in a series path containing the source 20 and the discharge path of the tube. Hence, as the impedance of the microphone for unidirectional current varies, a corresponding varying 15 electromotive force will be impressed across the tube between the cathode and the anode. Likewise, as the impedance of the microphone for high frequency currents varies, the energy supplied to the oscillatory 20 circuit 13, 14 will be caused to further vary, since the varying current representing this energy must flow through the path comprised by the microphone 32 in shunt to the resistance 30, the effective resistance of 25 which path varies as the resistance of the microphone varies.

Coupled to the inductance 13 may be any 30 device for utilizing the modulated oscillations produced, but in practice it will, in general, be desirable to amplify these oscillations. In the present instance the inductance 23 is included in the input circuit between the cathode 24 and the grid 25 of a 35 thermionic amplifier 22 of which the elements are enclosed in an evacuated vessel 26. The output circuit of the amplifier extends from the cathode to the anode 27 and contains a tuned circuit including capacity 28 and inductance 29. This tuned circuit is 40 preferably adjusted to be resonant to the frequency set up by the oscillator. Coupled to inductance 29 is the coil 12 included in an antenna circuit 10 grounded at 11. The antenna circuit serves to radiate the amplified 45 modulated oscillations.

For wire signaling the antenna circuit will be replaced by the usual conductive line.

The subject matter of this specification is divided from applicant's Patent No. 50 1,343,562, filed September 21, 1915, granted June 15, 1920. The novel features believed to be inherent in the invention are defined in the appended claims.

What is claimed is:

55 1. A wave generating system comprising a space discharge device having an anode, a cathode, and an impedance control element, input and output circuits for said device, energy transfer means connecting said input 60 and output circuits, a source of space current in series with said anode and cathode, means for varying the generated waves comprising a device whose impedance is controlled by and in accordance with sound 65 waves in series, as regards the flow of said

transferred energy, with said source external to said device.

2. A wave generating and transmitting system comprising a space discharge device having an anode, a cathode, and an impedance controlling element, input and output circuits for said device, means intercoupling said circuits, said input and said output circuits including a common portion, means for varying the generated waves comprising an impedance serially included in said common portion, and means in shunt to said impedance for controlling the fall of potential therethrough in accordance with waves of lower frequency.

75 3. A wave generating system comprising a space discharge device having an input circuit between a cathode and an impedance controlling element, a loop circuit, a lead from said cathode to said loop circuit, and a device included in conductive relation in said lead responsive to sound waves for varying the impedance of said lead.

4. A modulating system comprising an electron discharge device having an electron emitting cathode, an anode, and a grid element, a tuned circuit containing inductance and capacity, means connecting said device to said tuned circuit whereby oscillations are set up in said tuned circuit; a conductive path connecting said device and said tuned circuit, said path constituting a part of a complete circuit which is coupled to a portion of said tuned circuit and which includes a space within said device, and means conductively connected in said path for varying the impedance thereof in accordance with signaling waves.

90 5. In a signaling system, the combination of an electron discharge device having an electron emitting cathode, an anode, and a grid element, a tuned circuit containing an inductance and a capacity connected at its terminals to the grid and the anode of said device, a path conductive to high frequency 95 current connecting the cathode of said device to said tuned circuit, and means conductively connected in said path for varying the impedance of said path in accordance with signaling waves.

100 6. A modulating system comprising a tuned circuit, a discharge tube having input and output circuits connected to said tuned circuit for the generation of oscillations therein, an electron emitting cathode and an anode in said tube, a source of space current in series with said cathode and anode, and means whose impedance varies in response to sound waves connected in conductive relation with said source and said cathode.

105 7. A modulating system including a discharge tube having an anode, a cathode and a grid, a circuit between said anode and cathode including a source of energy, a 110

microphone connected conductively in said circuit, a high frequency input circuit connected to said cathode, a high frequency output circuit connected to said anode, and an energy transferring coupling between said circuits.

8. An oscillation generating system comprising a space discharge device having an anode, a cathode, and a grid, circuit arrangements connected to said device for the generation of oscillations thereby including a grid circuit, an anode circuit, and a circuit for determining the frequency of the oscillations, a space current path external to said device between said anode and cathode including a source of electromotive force, and a device conductively connected in said path whose impedance varies in response to sound waves acting thereon.

10 9. Apparatus for producing a modulated wave which comprises a source of energy for producing unidirectional current, a device supplied with current from said source for converting the energy of the supplied unidirectional current into oscillations, a conductive circuit through which said current flows, a conductive circuit through which at least a portion of said oscillations flows, an impedance-containing element common to 15 said circuits, and a device for varying the impedance which said impedance-containing element offers to the flow of said current and to the flow of said oscillations in accordance with a modulating force according to 20 which said wave is to be modulated.

10 10. A modulating system including a space discharge device having an anode, a cathode, and a grid, a path symmetrically conductive to direct current between said grid and said cathode, a path conductive to direct current between said anode and said cathode, and a sound wave controlled variable impedance conductively connected in said first mentioned path.

45 11. In a transmitting system, a work circuit, and means for generating and transmitting the generated oscillations to said work circuit comprising an evacuated vessel containing grid, plate and filament electrodes, a circuit connecting said grid electrode with said filament electrode, a circuit connecting said grid electrode with said plate electrode,

and a signalling device conductively included in said grid filament circuit.

12. In a transmitting system, a work circuit, and means for generating and transmitting the generated oscillations to said work circuit comprising an evacuated vessel containing grid, plate and filament electrodes, a circuit connecting said grid electrode with said filament electrode, a circuit connecting said grid electrode with said plate electrode, and a device whose impedance for both direct and alternating current of the frequency being generated varies by and in accordance with sound waves acting thereon conductively included in said grid filament circuit.

13. In a radio telephone transmission system, a work circuit, means for generating and transmitting the generated oscillations to said work circuit comprising an evacuated vessel containing grid, anode and cathode electrodes, a circuit connecting said grid electrode with said cathode electrode, a circuit connecting said grid electrode with said anode electrode, and a microphone conductively included in said grid-cathode circuit.

14. In an electrical signaling system, an evacuated vessel containing two cold electrodes and one hot electrode, an oscillating circuit comprising an inductance and a capacity in parallel which is connected across two of said electrodes, a tap connection between an intermediate point of said circuit and the third electrode, said point being separated from each of said two last-mentioned electrodes by impedance means, and a signal transmitting device included in said connection.

15. In an electrical signaling system, an evacuated vessel containing two cold electrodes and one hot electrode, an oscillating circuit comprising an inductance and a capacity in parallel connected across two of said electrodes, a tap connection between an intermediate point of said circuit and the third electrode, a signaling device in said connection, and a path other than said tap connection between two of said electrodes including a source of current.

In witness whereof, I hereunto subscribe my name this 27th day of May A. D., 1920.

RAYMOND A. HEISING.
